US0D1101592S

(12) **United States Design Patent** (10) **Patent No.:** **US D1,101,592 S**
(45) **Date of Patent:** **** Nov. 11, 2025**

(54) **MECHANICAL CONNECTOR FOR BAND**

(71) Applicant: **Google LLC**, Mountain View, CA (US)

(72) Inventors: **Gina Reimann**, Los Gatos, CA (US);
Maj Isabelle Olsson, Sunnyvale, CA (US); **Peter Michael Cazalet**, Los Gatos, CA (US); **Christoph Gredler**, Mountain View, CA (US)

(73) Assignee: **Google LLC**, Mountain View, CA (US)

(**) Term: **15 Years**

(21) Appl. No.: **29/941,927**

(22) Filed: **May 13, 2024**

Related U.S. Application Data

(62) Division of application No. 29/810,358, filed on Oct. 4, 2021, now Pat. No. Des. 1,035,478.

(57) **CLAIM**

The ornamental design for a mechanical connector for band, as shown and described.

DESCRIPTION

FIG. 1 is a front perspective view of a mechanical connector for band, showing our new design;

FIG. 2 is a rear perspective view thereof;

FIG. 3 is a front plan view thereof;

FIG. 4 is a back plan view thereof;

FIG. 5 is a right side view thereof;

FIG. 6 is a left side view thereof;

FIG. 7 is a top plan view thereof; and,

FIG. 8 is a bottom plan view thereof.

The broken lines in the drawings represent portions of the mechanical connector for band and form no part of the claimed design.
